CONTAINER SEALING MEANS

George J. Meyer, Milwaukee, Wis.

Application December 31, 1931, Serial No. 584,036

2 Claims. (Cl. 215—38)

The invention relates to containers, such as bottles, jars, and the like, and to closures therefor.

An object of the invention is to provide a container, such as a bottle or the like, having a slightly tapered sealing surface about its side walls for receiving thereon the side walls of a cup-shaped closure which is pressed into place, and which is capable of adapting itself to slight irregularities of the sealing surface of the container, the sealing surface being of such character as to minimize damage thereto and even if damaged presenting ample surface for securing a perfect seal.

Another object of the invention is to provide a cup-shaped closure having a resilient liner or packing within the side walls thereof for engaging the sealing surface of the container onto which the closure is pressed.

A further object of the invention is to provide a cap in which the liner is formed of a material capable of being softened by heat as the closure is applied to the container to thereby secure a permanent seal.

A further object of the invention is to provide a vitreous container which is of strong and durable construction and in which the apertured portion thereof is provided with spaced circumferentially arranged projections, the projections protecting the cap sealing surface of the container, presenting ledges or abutments to facilitate prying off the closure, and presenting cam surfaces for engaging lugs on a closure for drawing the closure onto the container, the spaces between the container projections permitting an opener to be applied to the cap.

A further object of the invention is to provide a container closure having longitudinally extending tongues which are accommodated within the spaces between the container projections and are adapted to be wired or otherwise secured to the container for additional sealing purposes.

The invention further consists in the several features hereinafter set forth and more particularly defined by the annexed claims.

In the accompanying drawing, Fig. 1 is a sectional elevation of the neck portion of a bottle embodying the invention and carrying a closure of the invention;

Fig. 2 is a top view of the bottle;

Fig. 3 is a fragmentary side view of the neck portion of the bottle showing a modified form of closure applied thereto;

Fig. 4 is a sectional view of the neck portion

of the bottle taken along the line 4—4 of Fig. 2;

Fig. 5 is a fragmentary side view of the neck portion of the container, showing in section another modified form of closure applied thereto, and.

Fig. 6 is a bottom view of the closure shown in Fig. 5.

In the drawing, the numeral 10 designates a container of vitreous material, here indicated to be a bottle. The neck portion 11 of the bottle 10 is provided with an enlarged head 12 having a smooth exterior conical sealing surface 13 converging upwardly, the conical surface being slightly tapered in the ratio of approximately 1 in 16. The conical surface 13 merges at its lower 15 portions into a cylindrical surface 14.

A plurality of radial projections 16 are integrally formed on the neck portion 11 of the bottle and extend upwardly to the conical surface 13. The projections 16 are rounded at their side edges, as seen in Fig. 2, and at their upper edges present ledges 17 for receiving a prying tool, as hereinafter described. The projections 16 protect the conical sealing surface 13 from chipping or other damage. The lower edges of the projections 16 are provided with cam surfaces 18 for engagement with parts of a closure, as hereinafter described.

In that form of the invention shown in Fig. 1, the bottle is provided with a cup-shaped sealing cap 19 which is pressed onto the slightly conical surface 13 of the bottle. The sealing cap is formed of sheet metal and is provided with a resilient liner or packing sheet 20, which may be formed of paper, rubber, parchment, composition, or other material, best suited for the goods to be sealed in the container, such as milk, wine, beer, or carbonated beverages. The metal selected for the cap may be of various kinds; lacquered black steel would be suitable for milk bottles; tinned steel would be suitable for carbonated beverages; and copper or bronze for champagne and wines, etc. The metal is preferably rough on its inner side to secure better adhesion of the resilient liner. The lined caps 45 may be formed by any suitable process such as that disclosed in my co-pending application for sheet metal processing, Serial No. 339,174, filed February 11, 1929.

The side walls of the cap have substantially 50 the same taper as the head of the bottle, thus permitting the cap to be firmly pressed onto the bottle without damaging the liner. The caps when pressed onto the bottles will adapt themselves to varying diameters or slight variations 55

in rotundity of the bottle heads, the side walls of the caps being sufficiently deformable for this purpose. The caps will have a uniform sealing pressure regardless of such variations, if a uniform capping pressure is applied. Even if the conical surface 13 of the bottle head is damaged, it will still have ample area for a perfect seal; whereas, if the fragile top sealing edge of the conventional type of bottle is chipped, the bottle must be discarded. The taper selected for the side walls of the bottle head is sufficiently below the angle of slip to in most cases require a greater pressure to remove the cap than to apply it to the container, particularly after the cap has set a short time. The fit of the cap on the bottle is sufficiently tight so that it can easily withstand considerable internal pressure in the bottle, such as may exist when the bottle contains a carbonated liquid. The cap is retained in sealing engagement with the bottle by the peripheral tension set up in the side walls of the resilient cap during the application of capping pressure. The elasticity of the deformable sheet metal cap maintains this sealing tension, and the yielding character of the cap permits the use of a comparatively thin liner. When the cap is applied, the side walls are stressed considerably, but preferably without exceeding the elastic limit of the metal.

30 To loosen or remove the cap, a prying tool may be inserted between the ledges 17 and the lower edge of the cap. The hooked or cut end of a tool may also be entered between the head and the side walls of the cap, the spaces between the lugs 16 providing clearance for this purpose. The lower edge of the cap may be provided with a bead 19' to re-enforce and stiffen the cap, the outturned lower edge of the liner being clamped within the bead. The cap is preferably of such character that it will be destroyed or damaged in removal. The bead 19' prevents excessive stretching at the edge of the cap side wall so that this edge is approximately as resistant to stretch as other portions of the cap side walls.

40 In some instances, the liner or packing for the cap may be formed of a heat-softened material, such as lacquer, wax, or composition, the cap being heated during its application to soften the liner and thereby secure a permanent seal. This type of seal may be used with bottles containing champagne and other liquids which are kept sealed for many years.

45 In the modified form of construction shown in Fig. 3, the cap 219 is provided with integrally formed tongues 221 which lie in the spaces be-

tween the bottle projections 16 and have their lower ends crimped over, or otherwise secured to a sealing wire 222 or other sealing band surrounding the bottle neck below the projections 16.

5 In the modified form of construction shown in Fig. 5, the bottle 10 is provided with a bottle cap or hood 219 having a resilient liner 220 engageable with either the top or tapered surface of the bottle head, or with both of these surfaces. The cap 219 is provided with an enlarged skirt 10 221 which surrounds the bottle projections 16 and is provided with lugs 222 at its lower edge engageable with the cam surfaces 18 of the bottle projections 16. The cap 219 is drawn into sealing engagement with the bottle by the cam engagement between the lugs 222 and cam surfaces 18 when the cap is given a partial turn. This type of cap or hood is suitable for temporary use after the other sealing cap is removed. In applying or removing the cap 219, the lugs 222 pass through the spaces between the bottle projections 16. In some instances, the liner may be omitted from the cap 219. When the cap is provided with both side and top sealing surfaces, the cap is capable of use for both shipping and temporary 20 service, thus dispensing with the need for an additional cap. The side seal, which is the shipping seal, is established without engaging the cap lugs on the container cam surfaces, the cap being pressed onto the bottle in the same manner as 25 the cap of Fig. 1. The removal of the cap preferably destroys the side seal, and the cap is thereafter capable of temporary or service use, the top seal being established by the cam connection between the cap and the bottle. 35

What I claim as new and desire to secure by Letters Patent is:

1. A container closure, comprising a sheet metal cap having a skirt provided with an out-turned bead, and a packing liner for said skirt having a reversely turned edge portion extending over the entering edge of said skirt and clamped in place by said bead to resist relative shifting of the liner and skirt when the closure is forced 40 axially onto a container.

2. A container closure, comprising a sheet metal cap having a skirt provided with an out-turned bead at its entering edge, and a packing liner for said skirt having a portion clamped in place between said bead and the outer face of said 45 skirt to resist relative shifting of the liner and skirt when the closure is forced axially onto a container.

GEORGE J. MEYER.
